UNITED STATES PATENT OFFICE.

OLLIE T. NELSON, OF SEATTLE, WASHINGTON.

BOILER.

1,196,140.

Specification of Letters Patent. Patented Aug. 29, 1916.

Application filed June 9, 1914. Serial No. 343,985.

To all whom it may concern:

Be it known that I, OLLIE T. NELSON, a citizen of the United States, and resident of Seattle, in the county of King and State of Washington, have invented certain new and useful Improvements in Boilers, of which the following is a full, true, and exact specification.

This invention relates to boilers, and more especially to those of the horizontal tubular type, in which baffles are used to deflect or guide the heat in the desired direction.

The principal object of my present invention is to improve the construction shown and described in my application for patent serially numbered 754136 filed January 30, 1913, in that the baffle in my present construction is an integral part of the boiler shell itself and is thereby kept at a low temperature by having water against its inner surface at all times, thus preventing excessive heating which would cause more rapid deterioration of the baffle, and therefore require more frequent renewals of the same than would otherwise be necessary. I attain these objects as will be more fully hereinafter described and explained, illustrated in the accompanying drawings and pointed out in the appended claim.

In the drawings, Figure 1 is a side elevation of a boiler setting with part of the boiler and baffle in section. Fig. 2 is a rear end elevation of the boiler, showing the baffle.

Referring now more particularly to the drawings, reference numeral 1 designates the boiler shell, to the ends of which the tubes 2 are secured.

3 designates the boiler setting; 4, the grates; 5, the smoke pipe; 6, the combustion chamber; 6^a, the door of the said chamber, which may have a finger piece 6^b. The baffle is formed by offsetting the rear end of the boiler, as plainly shown in the drawings, and facing the undermost part of the offset portion with a plate 7, which forms the baffle proper. This plate 7 is here shown as welded or otherwise securely joined at 7^a, but it is obvious that such welding could be dispensed with.

The burning gases from the fires upon the grates 4, passing backwardly and upwardly in the direction of the arrows in Fig. 1, through the combustion chamber 6, strike

the baffle plate 7 which deflects the said gases through the tubes 2 which lie below the horizontal plane of the baffle plate 7. The burning gases pass through those of the said tubes 2 which lie beneath the horizontal plane of the baffle 7 to the forward end of the boiler and return through the tubes 2 which lie above the said plane, and thence out through the smoke pipe 5. It will be readily understood that the burning gases striking the baffle plate 7 would quickly burn out the said baffle plate except for the presence of the water against the inner surface of the said baffle plate. The water of course absorbs and dissipates the heat from the baffle plate, thus preventing overheating.

As stated, the baffle plate 7 is integral with the boiler shell itself, being welded into one with the rear end of the boiler, and therefore involves less handling of the parts in the setting up of the boiler, and in general repairs to the same.

Structural changes in regard to the exact position and general contour of the baffle plate, etc., will readily suggest themselves to others skilled in the art without departing from the spirit and scope of the invention, and I therefore desire to avoid being limited to the exact construction herein shown and described except as limited by the appended claim.

Having described my invention, what I claim as new and desire to protect by Letters Patent is—

The combination with a cylindrical horizontal fire tube boiler having upper and lower semi-circular and tubed rear end members, of a solid water cooled metallic baffle formed by a single semi-circular offset along a diametrical plane between said semi-circular end members at the rear end of the said boiler proper, whereby a space is left between the lower half of the rear end of said boiler and a boiler setting upon which the upper half of said rear end rests, for the purpose of allowing a free gas passage to the tubes of said boiler below the said baffle and at the same time cutting off free passage to the tubes above the said baffle.

OLLIE T. NELSON.
